UNITED STATES PATENT OFFICE.

PEDER PEDERSEN AND DEWITT C. MILLER, OF OMAHA, NEBRASKA.

CAR-COUPING.

SPECIFICATION forming part of Letters Patent No. 447,718, dated March 3, 1891.

Application filed October 13, 1890. Serial No. 368,017. (No model.)

To all whom it may concern:

Be it known that we, PEDER PEDERSEN and DEWITT C. MILLER, citizens of the United States, residing at Omaha, in the county of Douglas and State of Nebraska, have invented 5 a new and useful Improvement in Car-Couplings, of which the following is a specification.

This invention has relation to new and useful improvements in self-coupling car-couplings.

The object of this invention is to provide a simple self-acting car-coupling that may be attached to any car now in use, and be so constructed that it may be used with the ordinary link and pin; and in furtherance of this object the invention consists in the construction, combination, and arrangement of parts, as hereinafter more fully described, 15 and finally pointed out in the claims.

Figure 1 in the annexed drawings shows a top view of my improved coupling. Fig. 2 shows a sectional elevation thereof. Fig. 3 illustrates a transverse sectional view thereof. Fig. 4 shows a sectional view of the sliding connecting-link, and Fig. 5 shows a top view of the coupling-link.

Similar letters of reference refer to corresponding parts.

A in the drawings shows a draw-head of the usual form of construction, which is provided with a suitable chamber. Within this chamber is provided with two pivoted jaws, (marked B B'), which are precisely alike in construction and pivoted at a suitable point within said chamber, as shown in Fig. 4. These jaws are so formed at their gripping ends that when in their closed position they will snugly hug and accommodate a duplex spear-shaped link C, as shown. These jaws are held within the draw-head by means of suitable bolts C' C', which pass entirely through the draw-head, and thus pivotally hold the jaws within the head. The jaws are further provided with two shoulders surrounding the bolts, upon which said jaws ride, as shown in Fig. 2. The stem or rear part of the jaws is but half the thickness of the jaws proper, so that one stem may ride upon the other. These stems are further provided with suitable slots, 50 which are adapted to accommodate a pin D,

which passes through the draw-head and resting without both at the top and bottom within two similar sliding links E, which are adapted to slide within suitable longitudinal guideways F upon the outside of the draw-head, as shown in Figs. 1 and 2.

The sliding links E, one of which is shown in section in Fig. 3, are provided with an annular opening at one end adapted to accommodate the pin D, while the other is provided with a projecting lug e, one projecting above and the other below the draw-head, and working within suitable bearings of the bifurcated actuating-lever H, as illustrated 65 in Figs. 1 and 2.

The actuating-lever H, which is of metal, is provided with suitable bearings adapted to contain the bolt K and upon which it has pivotal movement. The jaws B B' are actuated by means of this lever, which may be worked from the deck of the car by means of a chain and brake-wheel, or below by means of a hand-lever, as shown in the figures.

Within the chamber of the draw-head A 75 and upon each side thereof are affixed the bow-springs L L', which work against the jaws B B' and tend to keep them in a locked position.

The pin D, which rests within the sliding 80 links E E', and the slotted stems of the jaws B B', is further guided and works within two longitudinal slots within the top and bottom portions of the draw-head, as will be understood by referring to Fig. 4.

The operation of our device is very simple. When a coupling is to be made, the operating-lever H is forced toward the dead-wood, and being pivoted near the center the curved arms are carried forward, and they being provided 90 with the slotted bearings containing the lug e of the sliding links E carry said links forward within their guideways, and these two links being connected by means of the pin D in turn carry that pin forward within its guideway slot. Now, as this pin rests within the slotted stems of the jaws B B' and has a fixed direction, it will be readily understood by all those conversant with the art to which this invention relates that the forward or gripping 95 ends of the jaws B B' will be carried readily outward as the pin D moves forward within 100

the stems, thus forcing them into an open position. The lever II may be locked in its extreme position and so keep the jaws open. However, when two cars are to be coupled, it is simply necessary to fix the coupling C within one of the draw-heads and then let the cars bunt, which will force the spear-head of the pin within the jaws, the springs L L of which readily give way, and thus permit the entering of the pin independent of the lever II.

By the peculiar construction of the jaws B B' the cars may be uncoupled while in motion, as the jaws are so pivoted that while operating they work away from the pin. At the rear the coupling is further provided with a buffer-stem M, which is keyed to the draw-head in the manner shown and provided with a suitable coiled spring which works against the draw-head and stem M, and at the other end against a follower N, which works upon the reach-rods P P, as is usual in car construction of this class. The coupling-pin employed is a double-ended spear-head link, as is clearly shown in Fig. 5.

When it is desired to use the ordinary link and pin in connection with one coupler, it is simply necessary to lock the jaws in their open position, when a link and pin may be used, a hole adapted to contain the latter being provided for that purpose.

The device is exceedingly simple and may be attached to any car now using the ordinary link and pin.

Having thus described our said invention,

what we claim as new, and desire to secure 35 by United States Letters Patent, is—

1. In a car-coupling, the combination, with a recessed draw-head, of two pivoted jaws within said recess, a pin working within the slotted stems of said jaws, sliding links connected to said pin, an operating-lever connected to said sliding links, and a double-headed spear-shaped link, all arranged substantially as and for the purpose set forth.

2. In a car-coupler, the combination, with 45 a recessed draw-head, of two pivoted spring-actuated locking-levers A, pin and links connecting said levers to a suitable operating-lever, a double-ended spear-ended connecting-pin adapted to work between said jaws, and 50 a buffer-stem keyed to said draw-head, provided with a spring, all arranged substantially as described.

3. In a car-coupler, the recessed draw-head A, the pivoted spring-actuated jaws B B', 55 the pin D, link E, lever II, and the buffer-stem M, in combination with the pin C, all arranged and adapted to operate substantially as described.

In testimony whereof we affix our signatures in the presence of witnesses.

PEDER PEDERSEN.
DEWITT C. MILLER.
